(57) **CLAIM**

The ornamental design for a narrow belt drive wheel liner, as shown and described.

DESCRIPTION

FIG. 1 is a perspective view, from an approximately 45° angle, of a narrow belt drive wheel liner according to our design;

FIG. 2 is a front view thereof;

FIG. 3 is a top view thereof; and,

FIG. 4 is another perspective view, from an approximately 20° angle, thereof.
